CLAIM

The ornamental design for a cabin ceiling, as shown and described.

DESCRIPTION

FIG. 1 is a bottom view of a cabin ceiling showing our new design in an aircraft cabin;

FIG. 2 is a bottom view of the cabin ceiling of FIG. 1, which is shown separately for ease of illustration.

FIG. 3 is a forward perspective view of the cabin ceiling of FIG. 1 in an aircraft cabin;

FIG. 4 is a perspective view for the cabin ceiling of FIG. 1, which is shown separately for ease of illustration.

FIG. 5 is an aft perspective view of the cabin ceiling of FIG. 1 in an aircraft cabin; and,

FIG. 6 is another perspective view of the cabin ceiling of FIG. 1, which is shown separately for ease of illustration. In FIGS. 1-6, broken lines indicate environmental structure that forms no part of the claimed design.
